UNITED STATES PATENT OFFICE

FREDERICK L. FULLER, OF ILLION, NEW YORK, ASSIGNOR TO REMINGTON ARMS COMPANY, INC., A CORPORATION OF DELAWARE

CASH REGISTER

Original application filed November 19, 1918, Serial No. 263,125. Divided and this application filed May 4, 1926. Serial No. 106,598.

This invention relates to cash registers in general, and has more particular relation to interlocking mechanisms whereby it is necessary to depress a key of one class prior to a key of another class in order to release the machine for further operation.

This application is a division of the inventor's co-pending application, Ser. No. 263,125 filed November 19, 1918 to which reference 10 may be had for a more complete description of the cash register to which the present invention has been applied. While the improvements set forth in this application are shown applied to a particular type of cash 15 register illustrated in the parent application, the invention is not limited to this specific embodiment, as the improvements are of such a nature that they may be applied in various modifications to many other kinds 20 and principles of cash registers and accounting machines.

The invention relates more particularly to cash registers of that class in which the operating keys of different groups may be successively coupled or attached to a key coupler or a common member so that a number of keys may be successively attached to the key coupler and the operation of all of them then completed by giving the key coupler a full 30 movement by fully depressing any of the attached keys. The provision of means for thus permitting the successive connection of the keys to the key coupler renders it unnecessary to simultaneously depress all of the keys 35 which may be required at a given operation, so that their combined values as represented by more than one key may be indicated, registered and printed by one hand if desired.

The mechanisms whereby the above-mentioned functions and results are obtained usually have no means whereby it is necessary to depress keys of a certain class or group before keys of another class may be operated, and without the provision of such a device the 40 operator may, at will, successively depress keys in any particular sequence, and if so desired may operate the machine without depressing keys of a certain class. In cash registers of the type to which the present invention has been applied, it is desirable to make

special indications, such as the clerk operating the machine, departmental designations, or the like, so that each transaction will be completely identified. To effect such a result the present invention employs an improved 55 type of interlocking mechanism in connection with the coupling device whereby it is necessary to depress one of the special keys before the keys of other groups may be operated.

A practical objection which has been found in the use of that type of machine whereby the keys may be successively attached to the key coupler is that keys of certain groups may inadvertently be slightly depressed beyond a certain point and since the mistake 60 cannot be corrected the amount represented by that key would have to be indicated and registered whether it corresponds to the amount of the sale or not. It is an object of the present invention to provide improved 65 means associated with certain keys and in connection with the interlocking devices, whereby the key coupler may not be moved beyond a position in which keys may be connected therewith, even though the keys are operated violently and with considerable 70 force. This mechanism is positive in its action, precluding any possibility of the disarrangement of the machine performed either accidentally, or intentionally by prejudiced 75 persons.

It is a further object of the present invention to include pendants or key stops of the usual type whereby it will be impossible to depress more than one key in a certain group 80 preventing disarrangement of the differential devices with a corresponding confusion in the indication and printed record.

With these and other objects in view the invention consists in certain novel features of construction and combination of parts, the essential elements of which are set forth in the appended claims and a preferred embodiment of which is hereinafter described with reference to the drawings accompanying 85 and forming part of this specification.

Of said drawings:

Fig. 1 is a transverse sectional view of a cash register including the present invention, showing the operating keys, the differen- 100

tial mechanism, the totalizers, and a portion of the key interlocking mechanism.

Fig. 2 is a detail view showing the connection between the key coupler and the driving shaft, as well as the key coupling devices, and the full stroke mechanism.

Fig. 3 is a partial view, in elevation, of the back of the machine showing in detail the interlocking mechanism and the pendants associated with the various groups of keys all in normal position.

Fig. 4 is a view similar to Fig. 3, but showing the position that the interlocking devices occupy when a clerk's key has been partly depressed.

Fig. 5 is a view similar to Figs. 3 and 4 showing the position of the parts when a clerk's and amount key are fully depressed.

Fig. 6 is a top plan view of a portion of the interlocking mechanism.

Fig. 7 is a rear elevation of the machine showing a modification of the present invention, the parts being shown in normal position.

25 Figs 8, 9 and 10 are detail views of the modified form of the interlocking device shown in Fig. 7, showing the position the interlocking devices occupy when keys of two groups are moved to different positions.

Keyboard

The illustrative machine is provided with three classes of keys. There are three different groups of amount keys, one group for entering amounts from 1¢ to 9¢, one group for amounts ranging from 10¢ to 90¢ and the remaining groups, for amounts from \$1.00 to \$7.00 inclusive. Four transaction keys are also provided for denoting the type of transaction entered in the machine, and the remaining group of keys comprises two keys, designated as clerks' keys, "A" and "B".

45 The transaction keys which are shown in Figs. 1 and 3 are designated by reference character 20 and comprise a series of four keys for designating the following transactions "paid out", "charge", "no sale" and "received on account". Each of the transaction keys is provided with suitable key 50 caps bearing indicia to designate the type of transaction registered by that key. Each key is loosely mounted upon a transverse shaft 21 and is guided in its reciprocating movement at its forward end by means of slots 22 formed in the cabinet 23, and at its rearward end by slots 24 formed in a guiding plate 25 attached to a frame 26.

55 The amount keys comprise a series of keys, the rear ends of which are shown in Fig. 3 and designated by reference character 27, the keys being divided into groups as hereinbefore explained. The construction of the amounts keys is similar to the transaction keys. The clerks' keys of which there are 60 two, are designated by reference character 28

(Fig. 4) and are situated at the extreme left of the machine, and are likewise similar in construction to the amount and transaction keys.

Key coupler

70 As is usual in cash registering machines of the type used for illustration, there is provided a key coupler 29 journaled at 30 between the side frames, the key coupler resting upon the rear ends of all the operating keys. Mounted upon the nose of the key coupler 29 is a series of pivoted latch plates 31, a latch plate being provided for each group of amount and transaction keys. Reference to Fig. 1 shows that the pivotal points of the key coupler 29 and the keys are so related that the arc described by the key coupler 29 will intersect the arc described by the keys. Advantage is taken of the intersecting arcs for the purpose of latching and coupling the keys so that a depression of a single coupled key will result in a depression of all the other keys that have been attached to the coupler. This mechanism is well known in the art and will not be described in detail.

Driving mechanism

Connected to the key coupler 29 is a bifurcated plate 32 (Fig. 2) provided with two sets of rack teeth, 33 and 331, adapted to selectively engage a pinion 25 fast to a shaft 34 journaled between the side frames. When the key coupled is rocked by the keys plate 32 is vertically reciprocated, and the rack teeth 33 engage the pinion 35 on its upward movement, while the teeth 331 engage the pinion on its downward movement. By this means a complete reciprocation of the coupler effects a complete rotation of the shaft 34.

100 It is essential to provide a mechanism whereby once a registration has commenced it must be completed before a subsequent registration can be started. To this end there is attached to the shaft 34 a ratchet wheel 36 against which bears a spring-pressed full stroke pawl 37. It will be noted that a number of the teeth of the ratchet wheel 36 have been cut away and a single tooth 38 has 105 been provided for a special reason, to be pointed out hereinafter.

Coupling devices

110 The present machine is also provided with a device for attaching the amount or transaction keys to the key coupler at the beginning of their movement so that any desired number of keys may successively be depressed and attached, and the operation of all of these carried out to completely effect the indication and registration of their combined values by the depression of any of the keys so attached. The keys which have been attached 115 are given a full movement just as though they 120

all had been simultaneously depressed by the hands of the operator, and their full values are indicated, registered and printed. This enables the operator to indicate and register with one hand a registration requiring the 5 operation of two or more keys, since it obviates the necessity of spanning several keys with his hands in order to secure the simultaneous operation of the several keys. The 10 device for accomplishing this will now be described.

As stated hereinbefore there are mounted 15 on the key coupler 29 a plurality of spring-pressed latch plates 31. Each latch plate 31 is pivoted to the key coupler by means of rearwardly extending arms 39 (Figs. 1 and 2) fixed to the key coupler and which are apertured to receive the pivot studs 40 carried by ears 41 integral with the latch plates 31. A 20 spring 42 projecting into sockets formed in both the latch plates 31 and the key coupler tends to rotate the latch plate 41 until stopped by an arm 43 integral with one of the ears 41 contacting with the upper face of the key coupler. Each bank of amount and transaction 25 keys has associated therewith its separate latch plate 31, which may be operated independently of any other latch plate.

For the purpose of positively raising the 30 key coupler to what is known as the "coupling point" any of the amount or transaction keys may be employed, but in the present instance the special keys designated as "clerks" keys 28 alone can perform this function.

As will be pointed out hereinafter the amount and transaction keys are normally 35 locked against operation so that in order to operate the machine it is necessary for the operator to depress one of the clerk's keys. The group of clerks' keys are not provided 40 with a pivoted latch plate 31, but the key coupler has rigidly secured to it a block of the same height as the plate 31, and of a width sufficient to co-operate with the two 45 clerks' keys 28.

When a clerk's key is partially depressed it will raise the key coupler to a partially elevated position, the nose of the key coupler and the fixed clock entering a notch 44 formed 50 in the rear end of the clerk's key. By mechanism which will be described hereinafter, the clerk's key may be depressed but a limited distance prior to the depression of an amount or transaction key. This initial movement 55 of the clerk's key brings the key coupler to the coupling point and the movement of the key coupler to this position will effect a partial rotation of the driving shaft 34, moving the special tooth 38 past the full full-stroke 60 pawl 37 (Fig. 2), thus holding the key coupler at the coupling point and the clerk's key in its partially depressed position. At this time any of the amount and transaction keys may be similarly depressed and engaged with 65 the key coupler.

Whenever the key coupler has been raised to the coupling point the latch plates 31 mounted thereon will be above the notches 44 formed in the rear ends of the amount and transaction keys, and will bear against the edges 45 of the keys, which edges are arcs substantially concentric with the key coupler pivot points. When it is desired to attach an amount key to the partially raised key coupler the finger piece on the desired key 70 is depressed slightly. The rear end of the key is thus elevated, and the engagement of the edge 45 with the rear edge of its latch plate 31 will rock said latch plate counter-clockwise until the concentric edge 45 clears 80 the same. At this time the latch plate 31 will be free to rock clockwise under the influence of the spring 42 thereby permitting it to engage the notch 44 formed in the rear end of the depressed key. In this manner 85 any amount key is positively engaged or attached to the key coupler and in a similar manner any transaction key may be partially depressed so as to attach it to the key coupler. As previously described, the complete operation 90 of any of the attached amount or transaction keys will result in the simultaneous depression of all the keys which have been attached to the key coupler.

Differential mechanism

The differential mechanism and devices controlled by each of the various banks of amount keys are all similar in construction and operation and a description of one will 100 suffice for all.

Each of the amount keys, as shown in Fig. 1, is provided with an upwardly extending arm 48 carrying at its extreme end a roller 49 which co-operates with a slot having two branches 50 and 51 formed in cam plates 52. The cam plates 52, of which there is one for each key in a bank, are carried by a frame 53 loosely pivoted upon a transverse shaft 54. The slots 50 in the cam plates 52 105 are concentric with the shaft 54 while the slots 51 are eccentric with respect to the key shaft 21. From the foregoing it will be evident that upon the depression of an amount key a differential movement will be imparted from the frame 53. When the frame 53 is operated by a key of a certain bank the rollers 49 associated with the undepressed amount keys in the same bank, will play in the arcuate slots 50 which permit the upward tilting of 110 the frame 53 without interfering with the studs carried by the unoperated keys of that bank.

It will be understood that there is a differential frame 53 for each group of amount keys and transaction keys as well. Each differential frame has secured or connected thereto so as to be movable therewith, a segmental rack 55 (Fig. 1) the teeth of which are in continuous engagement with a pinion fast to 115 120 125 130

an item type wheel 56. Thus it is evident that when the keys are depressed the corresponding racks 55 are moved and are given a differential degree of movement so that the 5 item type wheels 56 will be rotated correspondingly. When suitable impression (not shown) means is actuated the item type wheels will print characters indicating the amount and type of the transaction entered in the 10 machine.

Below the item type carriers 56 are two totalizers 57 and 58, the upper totalizer 57 is for convenience designated as the "A" totalizer, and the lower 58 as the "B" totalizer. 15 These may be used for the purpose of registering amounts selectively controlled by the two clerk's keys 28 so that the related totalizer may be operated by means of the racks 55. The totalizer engaging mechanism and 20 associated devices comprise no part of the present invention and for this reason is not explained in detail in the present application.

Interlocking mechanism

25 It is desirable in machines of the class to which the present invention is applied to compel a clerk or operator of the cash register to depress his key in order that the proper indication and record of the clerk operating 30 the machine will be effected during each registration. As previously stated the clerks' keys are first given a partial movement, this movement operating the interlocking mechanism so that it will serve to unlock the keys 35 representing the type of transaction and the amount of purchase, thereby permitting the latching of these keys to the key coupler.

The mechanism whereby the above-mentioned results are obtained will now be described. Referring to Fig. 3 it will be noted 40 that the rear ends of the clerk's keys 28, transaction keys 20 and amount keys 27 extend through the slots 24 formed in the guide plate 25. The clerks' keys 28 co-operate with 45 a pendant 59, the series of transaction keys co-operate with a series of pendants 60, while each group of amount keys cooperate with their respective groups of pendants 61, all of which are pivoted to the frame 26, and lie 50 adjacent to the slotted plate 25. These pendants serve in the usual way to prevent the simultaneous operation of two or more keys in a group which would probably result in the disarrangement of some of the mechanisms and confusion in the printed record.

The pendants denoted by reference characters 62, 63 and 64, which as will be noted in Fig. 3 are located between the pendants of each group, are of a different form than the 60 other pendants, and are pivotally connected at their lower ends to a slide 65. Pivotally connected to the slide 65 is a latch member 66 provided with a downward extension 67 to which a spring 68 is connected, the opposite 65 end of the spring being connected to a stud

carried by the plate 25. The latch 66 is provided with an upward extension 69 which is bent forwardly at 70, as shown in Fig. 1 and then extends further upwardly vertically to form fingers 71 and 72 separated by a notch 73 provided for a purpose to be described hereinafter. The latch 66 is pivoted at one side of the slide 65, but is offset at 74 so as to extend to the other side of the slide 65, the offset portion being provided with a nose 75 which as shown in Fig. 3, normally abuts against the side frame 76.

It will be obvious from Fig. 3 that none of the transaction keys may be operated due to the fact that their pendants 60 and 62 are locked against oscillation by the latch member 66, since the nose 75 contacts with the side frame 76. Similarly none of the amount keys may be operated since their pendants 61 and 63 are locked against operation by reason of the fact that the slide 65 is held against movement by the latch member 66.

The pendant 59, however, is not normally locked and will permit the partial operation of one of the clerk's keys 28. When a clerk's key is partially depressed the rear end of the depressed clerk's key will engage the portion 70 of the latch 66, resulting in lifting the latch 66 from the position shown in Fig. 3 to the position shown in Fig. 4, and the lifting of the latch member 66 will bring the nose 75 to register with an aperture 77 formed in the side frame 76. The clerk's key is locked against further depression by the engagement of the bent portion 74 of the latch 66 with the lower edge of the slide 65. It will also be noted that it will not be possible to depress the other clerk's key 28 since it is locked by the pendant 59. The pendants for other groups of keys, however, are unlocked, since the slide 65 is now free to move, with the result that any of the other keys may partially be operated and latched to the key coupler, as previously described.

The initial movement of any key either in the transaction or the amount key banks will oscillate its associated pendant thereby moving the slide 65 to the right, (Fig. 5) and, the latching member 66 moving with the slide, the nose 75 enters the notch 77 of the side frame 76. Movement of the latching member 66 will carry the part 70 thereof out of engagement with the depressed clerk's key 28, and permit a full movement thereof, the clerk's key registering with the notch formed between the fingers 71 and 73, and the clerk's key to the left lying on the left side of the member 70 and the finger 71. Any selected key may now be fully depressed and the key coupler will carry with it all the keys latched thereto, including the clerk's key. When the keys are returned to normal the spring 68 will rock the latching member 66 and slide 65 back to their normal positions (Fig. 3),

and the transaction and amount keys are again locked against depression.

While the construction previously described is a very satisfactory means for accomplishing the desired results it is to be understood that it constitutes only one embodiment of the invention and that other forms of the invention may be used to accomplish the same results. For example, Figs. 7 to 10, inclusive show a modification which has been found satisfactory in operation, and is in some respects superior to the construction hereinbefore described. In this form of the invention the special pendants 62, 63 and 64 as well as the slide 65, the latch member 66 and associated elements have been dispensed with. In lieu of these parts a locking plate 78 is provided. As shown in Fig. 7 the plate 78 extends across the back of the machine and is provided with upwardly bent ears 79 and 80 which are pivoted to the side frames 76. The plate is normally held in a forward position by a spring 81 (Fig. 7) connected between the plate 78 and a stud carried by the right side frame 76. The lower edge of the plate designated by reference character 82 is a portion which is of sufficient length and suitably bent so as to overlie all of the various groups of amount keys and the group of transaction keys. It is so positioned normally (Fig. 8) as to overlie these groups of keys, and, therefore, prevent their operation since the rear ends of each of these keys contacts with the lower edge of the portion 82. The portion of the plate 78 opposite the rear ends of the clerks' keys, denoted by reference character 83 extends further backward and downward than the main part of the plate 76 and abuts against the rear end of each of the clerks' keys 28. Immediately above the clerks' keys the plate 78 is provided with a forwardly extending tongue or cam portion 84 which may be engaged by the rear ends of the clerks' keys for rocking the plate 78 backward when a clerk's key 28 is depressed. Immediately above the tongue 84 is located a stop 85 for terminating and positively stopping the clerks' keys after the initial movement has been given. The operation of this device is as follows: Each group of amount keys and transaction keys are normally locked against operation by the engagement of the rear ends of each of these keys with the lower edge 82 (Fig. 8) of the locking plate 78, and, therefore, none of these keys may be depressed. The clerks' keys, however, are unlocked since their rear ends are free to be moved and the depression of one of these keys will oscillate the pendant 59 (Fig. 7) which will serve to prevent the operation of the other clerk's key in a manner well understood. When a clerk's key is given its initial movement, the rear end, on account of its engagement with the cam portion 84 will rock the plate 78

clockwise as viewed in Fig. 8 until the depressed clerk's key is positively stopped (Fig. 9) by the engagement of its rear end with the stop 85. Rocking of the plate 78 slightly counter-clockwise brings the locking edge 82 out of locking engagement with the rear ends of the transaction and amount keys and releases them for operation. When any of these are partially depressed so that they may be latched to the key coupler, the rear end of the depressed key of any group engages a forward angular cam face 86 (Fig. 9) and rocks the plate 78 still further clockwise, which results in bringing the stop portion 86 from out of engagement with the rear end of the depressed clerk's key, and therefore, unlocking it for further operation.

As previously described any key which has been latched to the key coupler may be depressed still further carrying with it all of the keys (Fig. 10) so latched, resulting in a complete operation of the machine by the manipulation of a single key.

In describing the construction of the mechanism of the present improvements it has been necessary incidentally to give a thorough explanation of the operation of both the preferred form and the modification described, hence further description of the operation would be superfluous.

While the invention herein disclosed has been described in considerable detail and there has been specified the preferred forms of the parts with their relative arrangement and co-action, it is to be understood that these constructions merely are illustrative examples of an inventive concept susceptible of a variety of modifications all coming within the scope of the claims which follow:—

What is claimed is:

1. In a machine of the class described, the combination of a series of keys, a special key having an initial and a final movement in one direction, pendants for the series of keys constructed to prevent the operation of more than one key in the series, a normally effective locking device for holding the pendants in a position to prevent operation of any key of the series, and means controlled by the special key during its initial movement for disabling the locking device.

2. In a machine of the class described, the combination of a series of keys, a special key having an initial and a final movement in one direction, pendants for the series of keys, a locking device for holding the pendants in a position to normally lock any key of the series, and means controlled by the special key during its initial movement for disabling the locking device to release the series of keys for operation.

3. In a machine of the class described, the combination of a series of keys, a series of special keys normally unlocked, each having an initial and final movement in one direc-

tion, pendants for the series of keys, a locking device associated with the pendants whereby the first mentioned series of keys are normally locked against operation and means controlled by any of the series of special keys during its initial movement whereby the locking device is disabled to unlock the normally locked keys for operation.

4. In a machine of the class described, the combination of a series of keys having initial and final movements in one direction, pendants for the series of keys, a special key, a locking device associated with the pendants whereby the first mentioned series of keys are normally prevented from being operated, and means controlled by the initial movement of the special key for disabling the locking device to permit an initial depression of any of the series of keys.

5. In a machine of the class described, the combination of a series of keys, having initial and final movements in one direction, a special key having an initial and final movement in one direction, pendants for the series of keys, a locking device associated with the pendants whereby the first mentioned series of keys are normally prevented from being operated, means controlled by the initial movement of the special key for disabling the locking device to permit an initial depression of any of the series of keys, and a member common to all the keys whereby the initially depressed keys may be simultaneously and completely operated.

6. In a machine of the class described, the combination with a plurality of amount determining manipulative devices, means whereby operation of any of the said manipulative devices effects operation of the machine, a series of independently movable members co-operating with the manipulative devices, a locking device common to the movable members whereby the manipulative devices are normally locked against operation, a special manipulative device and means controlled thereby for disabling the locking device to permit a release of the normally locked manipulative devices.

7. In a machine of the class described, the combination with a plurality of amount determining manipulative devices, means whereby operation of any of the said manipulative devices effects operation of the machine, a series of pendants co-operating with the manipulative devices, a locking device common to the pendants whereby the manipulative devices are normally locked against operation, a special manipulative device and means controlled thereby for disabling the locking device to permit a release of the normally locked manipulative devices.

8. In a machine of the class described, the combination with a plurality of amount determining manipulative devices, means whereby operation of any of the said manipu-

lative devices effects operation of the machine, a special manipulative device, a series of pendants co-operating with manipulative devices, and an interlocking device co-operating with the series of pendants and special manipulative device whereby the keys of the two sets of manipulative devices are required to be operated in a predetermined sequence.

9. In a machine of the class described, the combination of a series of amount keys and a series of clerks' keys, a plurality of independently movable locking devices for normally preventing the operation of the amount keys and means co-operating with the clerks' keys for disabling the locking devices by a partial depression of one of the clerk's keys.

10. In a machine of the class described, the combination of two series of operating keys, a plurality of independently movable locking devices for normally preventing the operation of the keys of one series and means co-operating with the other series for disabling all the movable locking devices by a partial depression of one of the keys of the second mentioned series.

11. In a registering machine, the combination of two series of keys, a plurality of locking devices for normally preventing the operation of the keys of one series, means co-operating with the other series for disabling all the locking devices by a partial depression of one of the keys of the second mentioned series, means for preventing a complete operation of the keys of the second mentioned series, said means being disabled by the movement of a key of the first mentioned series.

12. In a registering machine, the combination of amount keys, transaction keys and clerks' keys, a plurality of independently movable locking devices for normally locking the amount and transaction keys against operation, means associated with the clerks' keys for disabling all the locking devices for unlocking the transaction and amount keys, stop means for arresting the movement of the operated clerk's key after an initial movement and means for disabling said stop means operated by the initial movement of any transaction or amount key.

13. In a machine of the class described, the combination of a plurality of sets of keys adapted to be given an initial and final movement, a member common to said sets of keys whereby the initially depressed keys may be simultaneously and completely operated, a pivoted member carried by the common member whereby the keys of one of the sets may be connected to the common member during their initial movements, and interlocking devices between the sets of keys requiring their depression in a predetermined sequence.

14. In a machine of the class described, the combination of a plurality of sets of keys

70

75

one set being adapted to partially move a member common to said sets of keys, a pivoted latching member carried by the common member whereby the keys of certain of said sets may be attached to the common member, and an interlocking device between the sets of keys requiring their depression in a predetermined sequence.

15. In a machine of the class described, the combination of a plurality of sets of keys one set being adapted to partially move a member common to the sets of keys, a pivoted latching device carried by the common member whereby the keys of the other set may be attached to the common member, and an interlocking device between the sets of keys requiring their depression in a predetermined sequence and acting to positively arrest the common member when partially moved by the keys of one set.

16. In a machine of the class described, the combination with a plurality of sets of keys, a member common to all the sets of keys adapted to partially move from normal by the keys of one set, interlocking devices requiring the operation of the keys in a predetermined sequence and means controlled by the interlocking devices for positively arresting the common member at its partially moved position.

17. In a machine of the class described, the combination with a plurality of sets of keys, a member common to all the sets of keys adapted to be partially moved from normal by the keys of one set, interlocking devices requiring the operation of the keys in a predetermined sequence, means controlled by the interlocking devices for positively arresting the common member at its partially moved position, and means controlled by the keys of another set for disabling the arresting means.

18. In a machine of the class described, the combination of two sets of keys the devices of one set being arranged to be given a partial operation as a prerequisite to the operation of keys of another set, a member common to all the sets whereby the keys may be simultaneously and completely operated, a series of independently movable members associated with one of the sets of keys whereby the keys of that set are normally locked against operation and connections controlled by the keys of the other set whereby the movable members are rendered ineffective to lock the normally locked keys.

19. In a machine of the class described, the combination of a set of keys, a series of pendants associated with the keys and adapted to be displaced thereby, a locking member for said pendants normally held against movement, a special key, and connections whereby the special key releases said member and said pendants for movement.

20. In a machine of the class described, the

combination of a set of keys, a series of pendants associated with the set of keys, a member whereby the pendants are locked against oscillation by the depression of the keys, a special key having an initial and final movement, and connections whereby the special key releases the pendants for oscillation during its initial movement.

21. In a machine of the class described, the combination of a set of keys, a series of pendants associated with the set of keys, a member whereby the pendants are locked against oscillation by the depression of the keys, a special key having a partial movement, an element common to said keys and adapted to be partially moved by the special key, and connections controlled by the special key whereby the special key moves the member to release the pendants for oscillation during the partial movement of the special key and common element.

22. In a machine of the class described, the combination of a frame member, a set of keys, a series of pendants associated with the set of keys, a latching member normally engaging a portion of the frame member whereby the pendants are locked against oscillation, an aperture in the frame member, a special key, and means whereby the special key moves the latching member to register with the aperture for releasing the pendants for oscillation.

23. In a registering machine, two series of keys, locking means for normally preventing the operation of the keys of one series and means co-operating with the other series for disabling the said locking means by a partial depression of one of the keys of the said second mentioned series, means for preventing a complete operation of the keys of the said second mentioned series, said means being disabled by the movement of a key of the first mentioned series.

24. In a registering machine, the combination of a plurality of series of operating keys, pendants for each series constructed to prevent the operation of more than one key of each series, locking means for holding the pendants of one series of keys in a position to prevent operation of the keys of that series and means operated by one of the keys of another series for disabling said locking means.

25. In a registering machine the combination of a plurality of operating keys, pendants for each series constructed to prevent the operation of more than one key of each series, locking means for holding the pendants of one series of keys in a position to prevent operation of the keys of that series and means operated by one of the keys of another series for disabling said locking means, said means comprising a latch engaging an abutment and a projection on said latch in the path of a key of the second mentioned series,

whereby one of said keys may displace the latch to clear the abutment, thereby unlocking for operation the keys of the first mentioned series.

5 26. In a registering machine the combination of amount keys, transaction keys and clerks' keys, means for normally locking the amount and transaction keys against operation, means associated with the clerks' keys
10 for unlocking the transaction and amount keys, stop means for arresting the movement of the operated clerk's key after a partial stroke and means for disabling said stop means operated by the initial movement of
15 any transaction or amount key.

27. In a registering machine, a series of amount keys and a series of clerks' keys, locking means for the amount keys comprising a member correlated with said amount keys for
20 movement thereby but normally precluded from such movement, and means whereby a partial depression of a clerk's key adjusts said member to a position permitting operation of the amount keys.

28. In a registering machine, two series of operating keys, locking means comprising a member correlated with the keys of one series for movement thereby but normally precluded from such movement, and means
30 whereby a partial depression of a key of the other series adjusts said member to a position permitting operation of the keys of the first mentioned series.

29. In a machine of the class described, the
35 combination of a series of amount keys, means whereby depression of any of said keys effects operation of the machine, a special key, pendants for the series of keys, a locking device for holding the pendants in a position to
40 normally lock any key of the series, and means controlled by the special key for disabling the locking device to release the series of keys for operation.

30. In a machine of the class described, a
45 series of amount keys, a series of special keys, pendants for both of said series of keys arranged in a common plane, means cooperating with said pendants for normally locking said amount keys against operation and
50 means controlled by said special keys for disabling said first-mentioned means to release the amount keys for operation.

FREDERICK L. FULLER.
